No Drawing. Filed Apr. 10, 1963, Ser. No. 271,867
6 Claims. (Cl. 29—25.3)

This invention relates to semiconductor devices and particularly to a method of adjusting certain specifications of transistors by controlling the nature of the ambient atmosphere in which they are sealed.

In the manufacture of transistors it is often desirable to adjust certain of the device characteristics to meet the specified needs of particular customers as well as to maintain the distribution of certain types of devices within the limits of their specifications. Such adjustments are usually made by using semiconductor material of different characteristics, adjusting geometric factors such as the base width of the device, or by altering major processing operations such as etching operations. These methods are troublesome, expensive and often rather slow since the feedback of information to optimize the processing adjustments may take from several hours to several days.

Accordingly, an object of the present invention is to provide a method of adjusting transistor characteristics that is inexpensive, easy and rapidly accomplished.

The invention features encapsulating the transistors with varying mixtures of drying agents and moistening agents so that the moisture level of the ambient atmosphere is maintained at appropriate levels according to the distribution of transistor characteristics desired.

This invention permits shifting of important device parameters such as current gain, saturation currents or storage time at will within rather broad limits determined by device design and previous process variables. This is accomplished by controlling the moisture level within the ambient atmosphere. The use of controlled ambient atmospheres is well-known to the semiconductor industry to stabilize and optimize transistor parameters but such systems in the past have provided a rigidly controlled moisture level whereas the present invention provides any desired useful moisture level, and changes from one level to another may be easily carried out.

The invention provides for adjusting the moisture level by adjusting the ratio of a reversible adsorbent such as molecular sieve in combination with varying amounts either of drying agents such as barium oxide (BaO) or moistening agents such as calcium sulfate hemihydrate ($\text{CaSO}_4 \cdot \frac{1}{2}\text{H}_2\text{O}$) and encapsulating these powders so formed with the transistors. The reversible adsorbent is prepared in any convenient manner. For example, it is convenient to store opened containers of molecular sieve powder in ovens at or near 200° C. After cooling in a dry atmosphere, the adsorbent is mixed with drying or moistening agents in the desired ratio. The ratio used determines the average value of the desired device parameter which will be obtained. The greater the proportion of drying agent, the drier will be the ambient atmosphere. As a general rule, in PNP germanium transistors, drier ambient atmospheres result in lower current and power gains, higher saturation currents, and lower storage times in switching applications. Thus, if high current gain is desired, a ratio is selected which will provide relatively more moistening agent than would be used with the adsorbent if lower current gains were desired. Or, if a lower storage time is desired, a dry atmosphere is obtained for this purpose by using adsorbent and drying agent together. Other characteristics, such

2

as breakdown voltages, are not so strongly affected by the moisture level, though some difference may appear.

The purpose of the moistening or drying agents is primarily to vary the amount of moisture contained in the reversible adsorbent. It is postulated that this amount of moisture determines the water vapor content of the encapsulated atmosphere in equilibrium with the powder in the encapsulation, which in turn affects the device parameters.

The advantages of this invention are:

(1) The moisture content of the adsorbent may be controlled at any preselected level, so that a continuous spectrum of controlled ambient materials is available.

(2) The powder is applied as one of the last steps in device production. If a need develops for more devices within a given range of parameters, a change in ratio may be used to shift the parameter distribution and thus provide the needed devices. All the devices, however, contain the same materials; they are merely present in different ratios. Possibly because the powders contain the same materials, the devices, unless other parameters are widely different, have about the same aging characteristics at temperatures as high as 125° C.

(3) The use of a good adsorbent, particularly molecular sieve, represents an attractive aspect in relation to reliability. While many adsorbents react only or primarily with water, molecular sieve, for example, can adsorb many other molecular and ionic species which may be present and may tend to degrade the device.

(4) The manner of application of this process to a typical device, a power transistor, is as follows: In normal production, industrial power transistors are electrolytically etched after assembly. After etching, rinsing and drying, they are stored in hot ovens until just before canning (encapsulation). The canning operation is performed on a large welding press. The cup-like can or lid for the transistor is placed in the lower electrode of the welder and a charge of the ambient atmosphere controlling materials is dispensed into it. The partial transistor assembly is then completed by placing it on the can, and the can is then welded to it.

Two alternate methods of dispensing the powder are used. In the first method, a charge of hot (and therefore dry) molecular sieve is dispensed into the can. (5) Then a charge of cold calcium sulfate hemihydrate ($\text{CaSO}_4 \cdot \frac{1}{2}\text{H}_2\text{O}$) is dispensed into the can. The ratio between the two components is determined by controlling the sizes of the respective charges. In the second method, which is preferred, the components are premixed in the proper ratio and placed in the dispenser. No heating need be used, but the chamber of the dispenser containing the mixture is flushed with a slow stream of dry, clean gas such as nitrogen or air to keep the powder from absorbing excess moisture. The appropriate volume of powder is dispensed into the can.

The second or preferred method provides better ratio control, more uniform composition of powder, and it is easier to change from one ratio to another.

The application of calcium sulfate hemihydrate-molecular sieve to a product line of industrial power transistors gave results as follows. The ratios used were (a) 100% molecular sieve, (b) 0.5 part calcium sulfate hemihydrate to 1 part molecular sieve, (c) 3.5 parts calcium sulfate hemihydrate to 1 part molecular sieve and (d) 5.0 parts calcium sulfate hemihydrate to 1 part molecular sieve. The parameter measured was I_B , with 10 amps collector current (I_C) and 2 volts collector voltage, as a measure of the D.C. current gain h_{FE} since they are related by

$$h_{FE} = \frac{I_C}{I_B}$$

Specifications for the device required an h_{FE} to be within the limits 10 to 30 which corresponds to a maximum I_B of 1000 millamps and a minimum of 333 millamps. Groups of ten transistors were canned each day for five consecutive days using each of the four listed compositions giving a total of fifty devices for each composition or treatment. The median values of I_B for each group were as follows:

Group	Ratio	Median I_B	Apparent percent Defective (Outside Specifications)
(a)	Molecular Sieve	941.0	33.5
(b)	0.5:1	801.0	6.1
(c)	3.5:1	658.6	0.0
(d)	5.0:1	621.2	0.0

An analysis of variance shows with 99% confidence that groups (c) and (d) are not significantly different from each other and that groups (a) and (b) are different from each other and from groups (c) and (d). Thus, in order to produce a maximum number of high h_{FE} units (low I_B) a ratio of 3.5:1 or 5.0:1 should be used. If treatment (a) were used, about a third could be expected to be outside specification for low gain while on the other hand powder (c) or (d) would yield essentially 100% good units for this parameter.

Other parameters were also affected but usually to a lesser extent. Differences between averages for breakdown voltages as measured from collector-to-base and emitter-to-base were not significant. The collector or emitter reverse currents varied with I_B but the difference was generally less noticeable than the differences in I_B .

If still drier ambients than those produced by the molecular sieve alone are desired, to establish lower h_{FE} values (higher I_B), a mixture of the molecular sieve and a dehydrating material such as barium oxide (BaO), in the proper ratio, can be used within the device enclosure. The system barium oxide (BaO)-molecular sieve was applied to a germanium mesa production line. Sixteen units were canned in each of five groups listed below, and the median values h_{FE} were calculated.

Group	Ratio	Median h_{FE}
1	100% BaO	31.3
2	75% BaO, 25% M.S.	37.7
3	50% BaO, 50% M.S.	46.3
4	25% BaO, 75% M.S.	42.7
5	100% M.S.	7.03

Thus, if one wishes to produce from a single lot of transistors, a certain percentage of the production having levels of h_{FE} higher than those produced by using barium oxide (BaO) alone, but lower than those produced by the use of the molecular sieve alone, one would employ the group 3 or group 4 material (having a ratio of, 50:50 or 25:75 BaO:molecular sieve). The relative level of the parameter h_{FE} , therefore, can be preselected by the selection of the proper ratio of the two materials.

The invention is not limited to just one or a few types of transistors but operate on a great variety of devices

using radically dissimilar technologies. It is an inexpensive non-critical process which is easy to apply wherever transistors are to be encapsulated in an ambient atmosphere.

We claim:

1. A method of controlling the electrical parameters of hermetically sealed semiconductor devices by establishing a desired level of gaseous moisture in the atmosphere within the devices, said method including the steps of, mixing a reversible adsorbent material and a chemically reactive moisture controlling material in a predetermined ratio to provide a mixture capable of establishing a preselected moisture level in said devices when sealed, placing said mixture in said devices, and sealing said devices.
- 10 2. A method of controlling the electrical parameters of hermetically sealed semiconductor devices by establishing a desired level of gaseous moisture in the atmosphere within the devices, said method including the steps of placing in said devices a mixture, comprised of a predetermined ratio of a reversible adsorbent material and a chemically active moisture controlling material capable of adjusting the moisture level in said devices when sealed to a level which establishes the electrical parameters of the devices at the desired values, and sealing said devices with said mixture therein.
- 15 3. The method of establishing a particular moisture level within an encapsulated semiconductor device, said method including the steps of, mixing a reversible adsorbent material with a drying agent in a predetermined ratio to provide the particular moisture level, placing said mixture within said device, and sealing said device.
- 20 4. The method of establishing a particular moisture level within an encapsulated semiconductor device, said method including the steps of, mixing a reversible adsorbent material and a moistening agent in a predetermined ratio to provide the particular moisture level, placing said mixture within said device, and sealing said device.
- 25 5. The method of establishing a particular moisture level within an encapsulated semiconductor device, said method including the steps of, mixing molecular sieve with calcium sulfate hemihydrate ($\text{CaSO}_4 \cdot \frac{1}{2} \text{H}_2\text{O}$) in a predetermined ratio to provide the particular moisture level, placing said mixture within said device, and sealing said device.
- 30 6. The method of establishing a particular moisture level within an encapsulated semiconductor device, said method including the steps of, mixing molecular sieve with barium oxide (BaO) in a predetermined ratio to provide the particular moisture level, placing said mixture within said device, and sealing said device.
- 35 7. The method of establishing a particular moisture level within an encapsulated semiconductor device, said method including the steps of, mixing barium oxide (BaO) in a predetermined ratio to provide the particular moisture level, placing said mixture within said device, and sealing said device.
- 40 8. The method of establishing a particular moisture level within an encapsulated semiconductor device, said method including the steps of, mixing barium oxide (BaO) with barium sulfate hemihydrate ($\text{BaSO}_4 \cdot \frac{1}{2} \text{H}_2\text{O}$) in a predetermined ratio to provide the particular moisture level, placing said mixture within said device, and sealing said device.
- 45 9. The method of establishing a particular moisture level within an encapsulated semiconductor device, said method including the steps of, mixing barium oxide (BaO) with barium sulfate hemihydrate ($\text{BaSO}_4 \cdot \frac{1}{2} \text{H}_2\text{O}$) in a predetermined ratio to provide the particular moisture level, placing said mixture within said device, and sealing said device.
- 50 10. The method of establishing a particular moisture level within an encapsulated semiconductor device, said method including the steps of, mixing barium oxide (BaO) with barium sulfate hemihydrate ($\text{BaSO}_4 \cdot \frac{1}{2} \text{H}_2\text{O}$) in a predetermined ratio to provide the particular moisture level, placing said mixture within said device, and sealing said device.
